Atty.

UNITED STATES PATENT OFFICE.

FRANCIS EVAN MOSS, OF WORTHINGTON, NEAR WIGAN, ENGLAND.

TOBACCO-PIPE AND THE LIKE.

1,249,171.

Specification of Letters Patent. Patented Dec. 4, 1917.

Application filed May 21, 1917. Serial No. 170,029.

To all whom it may concern:

Be it known that I, FRANCIS EVAN Moss, a subject of the King of England, residing at Worthington, near Wigan, in the county 5 of Lancaster, England, have invented new and useful Improvements in Tobacco-Pipes and the like, of which the following is a specification.

This invention has reference to tobacco 10 pipes or the like, and has primarily for its object to separate from the smoke in its passage from the bowl or tobacco part, to the mouth piece, condensed liquid, including nicotin, and dust, so as to prevent such 15 liquid, nicotin, and dust from passing to the mouth of the smoker.

In a pipe, or cigar or cigarette holder, according to this invention, there is disposed between the bowl or part in which the tobacco 20 is held, and the mouth piece, a cage or tubular appliance, say of metal, ebonite, or other suitable substance, having a plurality of inwardly projecting devices forming pockets or recesses or directing appliances 25 or devices, and inclined from the wall of the appliance toward the direction from which the smoke is coming; and apertures are provided in the walls behind these inclined parts, they being advantageously provided by stamping or cutting out and pressing inward, parts of the metal of the tube, to form the inwardly projecting baffles or 30 catching devices, of which there are a plurality or multiplicity in series, one beyond the other. For instance the inwardly projecting parts may be provided by cutting 35 tongue shaped devices in the tube, and bending the tongues inward, or by indenting same at the sides so as to form pockets.

40 The tubular appliance would be preferably fixed in the inner end of the removable mouth piece of the pipe or holder, which fits in the stem of same; and its inner end fits into a socket or recess near the bowl or 45 part of the pipe or holder in which the tobacco is placed, so that all the smoke has to pass on its way from the bowl or holder to the mouth piece into and through the devices. Around this tubular intercepting or 50 collecting device, and the interior of the stem, an annular space is provided for the liquid and dust to pass.

The drawing hereto annexed, of which Figure 1 is a longitudinal section; Fig. 2 is a cross section, taken through the stem.

55 Referring to the drawings, *a* represents

the bowl, *b* the stem, and *c* the mouthpiece, which in the case shown, makes joint with the stem by pushing it in the outer end of same. *d* is the tubular appliance, say of 60 ebonite, metal, or other suitable substance, the outer end of which fits in a socket in the bowl end of the stem *b*, and around which the annular space *e* exists.

The apertures of the appliance *d* are 65 marked *f*, and the inwardly projecting devices opposite these apertures *f*, are marked *h*, their inclinations being directed toward the direction in which the smoke is coming.

The device *d* is supported by the mouth 70 piece *c*, in which its outer end is fixed or fitted.

The inclined inwardly projecting parts *h* may be formed by cutting the tube *d* along three lines, and pressing back the cut parts 75 into the position shown.

The tubular device *d* will be withdrawn when the mouth piece *c* is withdrawn or removed, and the deposited matters can be removed from it, and the interior of the stem 80 and these parts can be cleaned.

The bore *i* of the mouth piece *c* leads at its inner end, from a point near the upper side of the tube *d*, so that any liquid or moist matters which are caught by and collected in the tubular devices *d*, will not 85 reach this bore *i*, and pass to the mouth of the smoker.

What is claimed is:—

1. In a device of the character described 90 comprising a stem having an opening therethrough which is reduced at one end, a mouth piece having an opening therethrough and fitted in the outer end of the opening in the stem, a cage supported in the 95 end of the mouth piece and the reduced end of the opening in the stem, forming a space between the cage and the wall of the opening, the cage having openings which form communication between the interior of the 100 cage and the space between the cage and the wall of the stem, and baffles projecting in the openings in the cage.

2. In a device of the character described 105 comprising a stem having an opening therethrough which is reduced at one end, a mouth piece having an opening therethrough and fitted in the outer end of the opening in the stem, a cage supported in the end of the mouth piece and the reduced 110 end of the opening in the stem, forming a space between the cage and the wall of the

opening, the cage having openings which form communication between the interior of the cage and the space between the cage and the wall of the stem, and inwardly and forwardly inclined baffles bent in the openings in the cage.

In testimony whereof I have signed my

name to this specification in the presence of two subscribing witnesses.

FRANCIS EVAN MOSS.
